and the like articles, and for various decorative purposes, such as window panes, display devices, signs, screens, and the like, however not differing in character from the ornamental device herein described. The ornamental device of the invention is particularly designed to simulate the effect of stained glass.

It is an object of the invention to provide an ornamental device, such as a window pane, display device, sign, screen, and the like, which will simulate the effect of stained glass, and which will be relatively inexpensive to produce, and which will be durable, attractive, and suitable for various decorative purposes.

UNITED STATES PATENT OFFICE

LORENZ W. F. CARSTEIN, OF FOREST HILLS, NEW YORK

MATERIAL FOR AND METHOD OF MAKING ORNAMENTAL DEVICES

Application filed September 19, 1929. Serial No. 393,617.

This invention relates to material for and method of making ornamental devices such as decorative window panes, simulating stained glass, display devices such as signs, screens and the like articles.

An object of this invention is to provide an improved decorative device adapted to give highly artistic visual effects simulating stained glass.

A further object of this invention is to provide a method of producing a device of the character described which may be carried out in a simple and economical manner.

A still further object of this invention is to provide an ornamental neat, compact, and rugged device of the character described which is adapted for execution in a wide variety of colors and designs for producing a wide variety of decorative objects, and which may be produced in a practical, simple, and cheap manner.

Certain features described and claimed in my co-pending application No. 381,902 filed July 29, 1929, are described but not claimed in the present case.

Other objects of this invention will in part be obvious and in part hereinafter pointed out.

With the above exception the invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention.

Fig. 1 is a top plan view of a piece of material or ornamental device made in accordance with the invention;

Fig. 2 is a fragmentary cross-sectional view taken through a portion of the material

described in Fig. 1;

Fig. 3 is a fragmentary cross-sectional view similar to Fig. 2 of a piece of material made in accordance with the invention illustrating the material after baking; and

Fig. 4 is a cross-sectional view taken on line 4-4 of Fig. 1.

shown in Fig. 1, and illustrating the method of making the same;

Fig. 3 is a fragmentary cross-sectional view similar to Fig. 2 of a piece of material made in accordance with the invention illustrating the material after baking; and

Fig. 4 is a cross-sectional view taken on line 4-4 of Fig. 1.

The accompanying drawings illustrates an embodiment of the invention in the form of a piece of material such as a window pane or the like ornamental device. It will be understood, however, that the drawings are merely illustrative and that the invention lends itself to embodiment in many forms such as display devices, signs, ornamental window panes simulating stained glass, and the like articles.

Referring now in detail to the drawings, 10 designates a piece of material embodying the invention here shown in the form of an ornamental pane comprising a plate 11 of glass or the like transparent material to which is attached a layer 12 of crinkly, wrinkled or stipled material made in the manner hereinafter appearing. Partially embedded in the crinkly layer 12 are strips 15 of lead or any other suitable opaque material. The strips 15 may be bent into any suitable shape or contour to produce a decorative effect simulating stained glass. As here shown, substantially radially extending strips 16 are provided dividing the device into a number of segments having various colors such as yellow segments 17, and orange segments 18. The crinkly layer 12 may extend entirely around the strip 15 to overlie and embed the same as shown at 20, said overlying portion however being preferably thinned. It will now be understood that by varying the configuration of the lead strips 16 and 15, and the colors of the portions between said strips, various designs may be readily executed. At the edge portions 11a of the glass plate 11 there are pro-

vided heavier border strips 21 of lead or the like material for providing a reinforcing edging or frame for the material. A second plate 23 of glass or the like transparent material may be placed over the strips 15, 21, and attached thereto by any suitable adhesive.

The display device 10 may be produced in the manner now to be described. To the upper surface 25 of the plate 11 is applied layer 12 made by first covering said surface with a layer 26 of varnish or the like non-vitreous, adhesive substance, as by brushing or in any other suitable manner. Strips or pieces of fabric such as china silk or the like material, colored or uncolored, are then applied on the adhesive layer 26 substantially in edge to edge relation to produce the desired design in the desired colors. As illustrated in the drawing, a number of strips 27 of orange fabric are laid on the adhesive coating 26 between strips 28 of yellow fabric, the adjacent edges 27a, 28a of said strips being substantially in contact. A second layer 30 of varnish or the like non-vitreous material is now applied over the adhered pieces of silk, for saturating the pores in the silk and acting as a suitable filler therefor. Preferably this second layer 30 dries at room temperature. However, the device thus far described may be placed in an oven for accelerating the drying. When the saturated silk layers have been sufficiently dried, the strips of lead 15 are placed over the meeting edges or seams formed by adjacent pieces of silk so as to cover such edges. The heavier strips 21 may then also be placed adjacent the side and end edge portions of the plate to form the border or frame. Another layer 32 of varnish or the like material requiring baking for drying may now be applied over the saturated silk and also over the lead strips for holding said lead strips in position. The plate may then be placed in an oven and baked. The outermost layer of varnish and the saturated or coated silk pieces are thereby caused to shrivel and form a layer having an irregular, corrugated surface 35 having turnings and winding ridges or wrinkles which produce a pleasing furrowed, rippled or crinkled effect visible from both sides of the device. It will be noted that the portions 36 adjacent the lead strips 15 and the portions 20 extending over said strips likewise become crinkled to produce the pleasing visual effects desired.

If desired, an additional coating of varnish requiring baking for drying may be applied over the layer 32, and the device further baked to further shrivel or draw in the coated layers to produce a stippled effect likewise simulating stained glass.

Also if desired, a second plate 23 of glass or any other suitable transparent material may be placed over the lead strips to cover

the front of the device, and attached thereto with any suitable adhesive material.

It will thus be seen that there is provided a device in which the several objects of this invention are achieved, and which is well adapted to meet the conditions of practical use. 70

As various embodiments might be made of the above invention, and as various changes might be made in the embodiment set forth, it is to be understood that all matter herein set forth or shown in the accompanying drawings is to be interpreted as illustrative and not in a limiting sense. 75

Having thus described my invention I so claim as new and desire to secure by Letters Patent:

1. Imitation stained glass comprising a plate, a baked crinkled layer on said plate, and an elongated strip on said layer. 85

2. An ornamental device comprising a transparent plate, a crinkled layer of translucent material adapted to crinkle upon heating at elevated temperatures on said plate and a strip of opaque material on said layer. 90

3. An ornamental device comprising a transparent plate, a crinkled layer of translucent material on said plate, and a strip of opaque material on said layer, said crinkled layer comprising a base of colored fabric saturated with a crinkling varnish. 95

4. An article of the character described comprising a transparent plate, a crinkled layer of translucent material on said plate and a strip of opaque material on said layer, said crinkled layer having a base comprising pieces of colored fabric substantially in edge to edge contact saturated with a material adapted to crinkle upon drying, said strips overlying the meeting edges of said fabric. 100

5. An article of the character described comprising a transparent plate, a crinkled layer of translucent material on said plate and a strip of opaque material on said layer, said crinkled layer at least partially embedding said strip. 105

6. Imitation stained glass comprising a plate, a crinkled layer on said plate, an elongated strip on said layer, and a second plate overlying said strip. 110

7. An ornamental device comprising a transparent plate, a crinkled layer of translucent material on said plate, a strip of opaque material on said layer, and a second transparent plate overlying said opaque strip. 115

8. An ornamental device, comprising a plate, a layer of baked crinkled material on said plate, said layer having a plurality of portions of different colors and a strip of opaque material on said plate. 120

9. An ornamental device, comprising a glass plate, a layer of crinkled material on said plate, said layer having a plurality of portions of different colors and a strip of opaque material on said plate, said strip over-

lying the dividing line between said portions.

10. An ornamental device, comprising a transparent plate, a layer of crinkled, varnish on said plate, and a strip of lead on said 5 layer.

11. An ornamental device, comprising a transparent plate, a layer of crinkled, non-vitreous material on said plate, and a strip of lead on said layer, said crinkled layer having a base comprising pieces of variously colored fabric saturated in baked varnish and in edge to edge relation, said lead strip overlying the meeting edges of said pieces.

12. An article of the character described 15 comprising a transparent plate, a layer of crinkled, non-vitreous material on said plate, and a strip of lead on said layer, said crinkled layer having a base comprising pieces of variously colored fabric superimposed in edge 20 to edge relation, said lead strip overlying the meeting edges of said pieces, and a second transparent plate overlying said strip.

13. An article of the character described, 25 comprising a transparent plate, a layer of baked varnish on said plate, and strips of lead having a predetermined configuration on said layer.

14. An article of the character described, 30 comprising a transparent plate, a layer of baked varnish on said plate, and strips of lead having a predetermined configuration on said layer, said layer having a base of colored silk.

15. An article of the character described 35 comprising a glass plate, a crinkled layer of non-vitreous translucent material on said plate, said layer having a base of fabric of predetermined color and configuration and strips of lead on said layer and overlying the 40 border of said fabric.

16. An article of the character described 45 comprising a plate, a crinkled layer of baked non-vitreous translucent material on said plate, said layer having a base of portions of fabric of predetermined color and configuration, strips of lead on said layer and overlying the dividing line between differently colored portions.

17. An article of the character described 50 comprising a plate, a crinkled layer of non-vitreous translucent material on said plate, said layer having a base of portions of fabric of predetermined color and configuration saturated with a crinkling varnish, strips of 55 lead on said layer and overlying the dividing line between differently colored portions, and a strip of lead on said layer at the outer edges of said plate.

18. An article of the character described 60 comprising a plate, a crinkled layer of non-vitreous translucent material on said plate, said layer having a base of portions of fabric of predetermined color and configuration, strips of lead on said layer and overlying the 65 dividing line between differently colored por-

tions, a strip of lead on said layer at the outer edges of said plate, and a second transparent plate mounted over said strips.

19. The process of making material imitating stained glass consisting in applying a 70 piece of textile material saturated with a varnish to a transparent plate, placing strips of lead on said saturated material and baking to produce a crinkled layer on said plate and embedding said strips.

In testimony whereof I affix my signature. 75
LORENZ W. F. CARSTEIN.
